UNITED STATES PATENT OFFICE.

EDWARD KAVANAGH, OF CHICAGO, ILLINOIS.

DESIGN FOR A COWL LAMP.

Application filed January 12, 1922. Serial No. 185. Term of patent 3½ years.

To all whom it may concern:

Be it known that I, EDWARD KAVANAGH, a citizen of the United States, residing at Chicago, in the county of Cook and State of Illinois, have invented a new, original, and ornamental Design for Cowl Lamps, of which the following is a specification, reference being had to the accompanying drawing, forming part thereof.

Figure 1 is a front elevation of a cowl lamp, showing my new design.

Figure 2 is a side elevation of the lamp, and

Figure 3 is a top plan view thereof.

I claim:

The ornamental design for a cowl lamp, as shown.

EDWARD KAVANAGH.
